UNITED STATES PATENT OFFICE.

LEO PEYTON BOTT, JR., OF LITTLE ROCK, ARKANSAS.

GAME.

Application filed February 19, 1925. Serial No. 10,259.

To all whom it may concern:

Be it known that I, LEO P. BOTT, Jr., a citizen of the United States, residing at Little Rock, in the county of Pulaski and State 5 of Arkansas, have invented certain new and useful Improvements in Games; and I do hereby declare the following to be a full, clear, and exact description of the invention, such as will enable others skilled in the art 10 to which it appertains to make and use the same.

This invention relates to improvements in games, and has for one of its principal objects the provision of a novel, useful, and enjoyable game, adapted particularly to be 15 used as a parlor game.

One of the principal objects of this invention is to provide, in a game, an element of chance, represented by various combinations 20 possible in the throws of a number of dice, preferably six, associated with coins, preferably imitation coins of paper or the like.

Other and further important objects of 25 this invention will be apparent from the disclosures in the accompanying drawings and following specification.

The invention, in a preferred form, is 30 illustrated in the drawings and hereinafter more fully described.

In the drawings:

Figure 1 is a perspective view illustrating the dice to be used with the improved game of this invention.

Figure 2 is a plan view illustrating the 35 paper or other coins of various denominations.

As illustrated in the drawings:

The reference numeral 10 indicates one of 40 a set of six dice, having one of its faces painted white and having its other faces painted red, yellow, blue, green, and purple, as indicated by the reference numerals 12, 14, 16, 18, and 20, respectively.

As illustrated at 22 in Figure 1, one of the 45 faces of one of the dice is painted black instead of purple, as illustrated at 20, thus leaving only five dice with a purple face, the one black square being the only square of that color.

The object of the game is to see who can 50 first secure five hundred (500) points "play-penny-a-point". As illustrated in Figure 2, paper coins of denominations one hundred (100), fifty (50), twenty-five (25), ten (10), 55 five (5), and two and one-half (2½) points are to be used. However, this paper money

is not essential, as other elements representing coins may be used, as chips or the like, or changes may be made in the denominations of the paper coins.

The players throw the dice in turn, but whenever six "reds" or one each of all colors (black excepted) are thrown the player has another turn. The black is known as the "stoker" and it will kill any hand thrown.

The points gained from the various combinations are as follows:

	Points.
1 black kills any hand.	
6 red	100 70
6 blue	50
6 yellow	50
6 green	50
6 white	25
5 purple	20 75
5 red	50
5 blue	25
5 yellow	25
5 green	25
5 white	12½ 80
4 reds	25
4 blues	12½
4 yellows	12½
4 greens	12½
4 purples	12½ 85
4 whites	5
3 pairs	25
3 pairs (1 of them red)	50
3 pairs (1 of them white)	12½
2 pairs	12½ 90
2 pairs (1 of them red)	25
2 pairs (1 of them white)	5
1 pair	5
1 pair (red)	10
1 pair (white)	0 95
1 of all colors but black	50

The above scores can be conveniently listed on a card to be used in playing the game.

It will be evident that herein is provided 100 an amusing and highly entertaining game in which dice may be used, and which will, at the same time, eliminate or avoid any objections which might be made to the use of actual dice having numbered dots on the faces thereof. The game, further, is conducive to developing the mind as stimulating the exercise of the mental faculties in rapidly calculating the value of each throw, and, further, in computing the totals of any number of 110 throws as the game progresses.

I am aware that many changes may be

2
made and numerous details of construction varied throughout a wide range without departing from the principle of this invention, and I therefore do not purpose limiting the 5 patent granted hereon otherwise than as necessitated by the prior art.

I claim as my invention:

1. A game, including a plurality of dice, all but one of said dice being similar and 10 having distinctive colors on the respective faces thereof, the odd dice having one of its faces colored with an additional distinctive color, said color being substituted for one of the original colors.
- 15 2. A game, including a plurality of cubical dice, all but one of said dice being similar and having six distinctive colors on the respective faces thereof, the odd dice having one of its faces colored black, constituting an 20 additional distinctive color.
3. A game, including a plurality of cubical dice, all but one of said dice being similar and having six distinctive colors on the respective faces thereof, the odd dice having

one of its faces colored black, constituting 25 an additional distinctive color, said color being substituted for one of the original colors, the rule of the game providing for forfeit of a hand thrown wherein the said black face appears uppermost.

4. A game, including a plurality of cubical dice, all but one of said dice being similar and having six distinctive colors on the respective faces thereof, the odd dice having one of its faces colored black, constituting 35 an additional distinctive color, said color being substituted for one of the original colors, the rule of the game providing for forfeit of a hand thrown wherein the said black face appears uppermost, and the rules 40 additionally providing for various combinations of points arranged in a predetermined sequence with various proper color combinations in the thrown dice.

In testimony whereof I affix my signature.

LEO PEYTON BOTT, Jr.
